UNITED STATES PATENT OFFICE

CHARLES H. GAGEN, OF MONTCLAIR, NEW JERSEY, ASSIGNOR, BY MESNE ASSIGNMENTS, TO AMERICAN AIR FILTER COMPANY, INC., OF LOUISVILLE, KENTUCKY, A CORPORATION OF DELAWARE

AIR CLEANER

Application filed March 28, 1927, Serial No. 179,128. Renewed January 16, 1931.

This invention relates to air cleaners of the class utilizing an oiled surface over which the air to be cleaned is caused to pass. Thus, substantially all dirt, dust and lint is removed 5 from the air by adhering to the oiled surfaces. To maintain the desired efficiency of such air cleaners, it is necessary from time to time to remove the dirt collected by the cleaner.

10 The most usual method for this operation with air cleaners used at present is to remove the stationary box-like cleaners from position and wash them by hand in hot water and soda. Another way used at present is 15 to give the cleaning surface a slowly continuous motion through a bath of oil. Still other processes used for cleaning are: To cause a drum-like structure to rotate continuously and sprinkle or spray oil through the 20 air cleaning element; to pump oil to the top of the cleaning device and permit it to flow down the surfaces of the cleaning element, etc. All these structures necessitate driving 25 mechanisms, including gearing adapted to bring about a great reduction in speed, and a comparatively costly construction of the cleaning elements.

The main purpose of the present invention 30 is to provide an air cleaning device equal or even superior in efficiency to the above mentioned prior types of devices, and utilizing the same efficient cleaning principle, but avoiding the necessity of being continuously driven, and the other costly arrangements of 35 the prior devices.

Another object of the invention is to provide 40 an air cleaning device of simplified and improved construction, and which is efficient and reliable in operation to a high degree. A further object of the invention is to provide 45 an air cleaning device which is adapted to be inserted into an air duct and which shall be particularly adapted to effectively cleanse the air passing therethrough.

50 A further object of the invention is to provide a device of the character described, which shall permit of a rapid and convenient cleansing of the parts thereof to remove accumulation of foreign substances.

A still further object is to provide a device

of the character described, having parts compactly arranged in an improved manner and to prevent leakage of air, and which can be constructed of sheet metal and standard structural steel elements. 55

Other objects will be evident, or pointed out hereinafter.

Accordingly, the invention takes the form shown in the drawings to illustrate one particular embodiment of the invention, the 60 scope whereof will be indicated in the appended claims. Said drawings illustrate my device in a manner which is somewhat out of proportion, the parts being relatively 65 large and heavy compared with the size of the whole device shown, this for the sake of clearness in details.

In the drawings:

Fig. 1 is a sectional elevation of the device, 70 taken on line 1—1 of Fig. 2.

Fig. 2 is a sectional elevation on line 2—2 of Fig. 3.

Fig. 3 is a plan section taken on line 3—3 of Fig. 1, and showing the device embodied 75 in an air duct or passage, with parts being omitted.

Fig. 4 is an enlarged fragmentary detail view of a locking mechanism, with parts omitted.

Fig. 5 is a detail view of a member that 80 serves to provide for air-tightness in the device, and

Fig. 6 is an enlarged fragmentary detail view of the side guide and sealing devices. 85

Referring in detail to the drawings, 10 is a frame embodying the mechanism constituting the invention, said frame being adapted for rapid and inexpensive manufacture on a large scale, and consisting therefore, of sheet metal plates and standard structural elements, such as angles or the like. The frame 90 10 is adapted for insertion and mounting directly in an air duct 11, shown here as of sheet metal construction (Figs. 2 and 3), so that the invention is utilizable for purifying and cleaning all of the air passing through said duct, as indicated by the arrows 11a. 95

More specifically, said frame consists of 100 vertical corner angles 12, and horizontal con-

necting angles 13 forming a rectangular structure. Disposed in the sides of said frame are open boxes 14 (Fig. 3) made of sheet metal and within which is housed the 5 mechanism for operating the air cleaning screens or filters 15.

To obtain the maximum efficiency in the 10 cleansing of air, or other gas, the screen structure is provided with a large number of closely spaced vertical plates 16. The plates 15 are of irregular formation to provide a maximum surface for contact with the air, and preferably each of the plates has a plurality of bends forming alternate angles extending longitudinally of the plate. The air flowing 20 through between said plates is thus caused to make a plurality of changes in direction.

The plates are coated with a suitable 25 viscous fluid, such as oil, or the like, whereby any particles of foreign matter or dust in the passing air is efficiently impinged or caught. The irregular flow of the air between the plates insures of a mixing action of the air so that all of the dust therein will 30 be removed by the oil coated screen.

A periodical washing of the screen structure is necessary to remove the accumulation 35 of dirt thereon, as mentioned hereinbefore, the plates being then coated with clean oil, and the air cleansing operation resumed. According to this invention, an improved arrangement is provided for novel coaction in the means for cleaning the screen structure and for coating the same with oil or other 40 liquids.

Specifically, an oil tank 17 is arranged in the base of the frame and below the screen structure. For economy of space, the latter is constructed of a plurality of filter units 45 or sections S, disposed in adjacent vertical planes, so that the filter or screen structure, no matter how high it extends when the filter units are in extended relation, can be wholly received within the oil tank when said structure is collapsed, said sections being then disposed in side by side relation in the tank. In this way, the plates of the screen or filter units are readily cleaned and coated with oil 50 or other liquids.

Each of the sections S consists of the plates 16, disposed between the vertical side frames 18 at the side edges of said sections, said sections being strongly bound into unitary structure by tie rods 18a extending transversely of said sections and passing directly through plates 16. Each of the structures thus provided is evenly balanced. The plates 16 are spaced apart by any suitable means such as 60 washers on the tie rods or projections on the plates and, this being conventional, has not been shown. A suitable number of vertical flat bars 19 are provided, spaced apart, on the front and rear sides of the sections S for a 65 purpose to be described hereinafter. Said

bars 19 are inset in the sections and are bound together by the through brackets 20.

The sections S have detachable engagement with one another by means of hooks 21 formed at the lower ends of the front bars 19 to engage in recesses 22 made in companion rear bars 19 modified as shown at 19a. Thus, when the uppermost of the sections S is raised by lifting mechanism soon to be described, its hooks engage the middle section, and those of the middle section engage in turn the third section, after a predetermined movement so that a completely elevated screen is presented. Similarly, when the sections are lowered into the oil tank, the hooks 21 will automatically 70 disengage and permit said sections to be disposed in side by side relation.

The lifting mechanism comprises a plurality of cable drums 23 fixed on a horizontal shaft or drum 24 journaled in the frame 10 above the screen structure. Cables 25 are secured to the drums and wound thereon, each cable being connected to the upper screen section at the lifting bars 19 thereof by any suitable standard means. The shaft or drum 24 can be rotated by any suitable power means, or manually, as by a continuous chain 26 at the side of the frame 10, having engagement with a sheave wheel 27 connected by its shaft 28 with a pinion 29, which in turn meshes with a gear 30 having a fixed coaxial pinion 31 that meshes with gear 32 on shaft 24. In this way, by pulling on chain 26 on the proper side thereof, the screen structure, through cables 25 and hooks 21 described hereinbefore, 80 can be raised into operative position, or lowered and collapsed into the oil tank. Any convenient brake mechanism may be incorporated into the lifting device in a manner 85 and for purposes well known in the art.

The invention provides means to permit the screens S to be raised or lowered with the maximum ease, and with the least wear or strain on the machine, while at the same time providing for tightness in the several parts 90 when the air cleansing device is in operation, so as to insure that practically all of the air will pass through the screens. Thus, cam members 33, 34, 35 and 36 are provided to 95 coact respectively with the upper, middle and lower screens at the bars 19 so as to press the screens together at their meeting horizontal portions, which are provided with felt strips 37 or other suitable material, for absolute air tightness (Figs. 2, 3 and 4). Said cam members are secured to horizontal shafts 38 which are disposed adjacent to the upper and lower edges of the screen sections S. The shafts are journaled in brackets 39 which are supported on vertical frame members 40. Each 100 of said shafts is connected by a pair of meshing bevel gears 41 and 42 to a vertical drive shaft 43 journaled at a side of the frame in brackets 44. The lowermost rocker shaft 38 has a handwheel 45 arranged exteriorly of 105

the frame 10, so that on rotation of the handwheel, and through the action of bevel gears 55 and 56 on said lowermost shaft 38 and on shaft 43, as shown, all of the rocker shafts 58 will be turned through a suitable angle to bring the cams to bear against the bars 19 on the screens S, the latter being elevated into operative position, so as to provide for the air-tight engagement of the screens in a lateral direction, as aforesaid. When it is desired to lower the screens into the oil tank, the handwheel is turned in an opposite direction to release the cams, so that the screens S can be lowered with a minimum of friction. A ratchet wheel 46 and a pawl 47 are provided to lock the cam mechanism in a desired position. A plate 48 at the top of the frame on a side of the screen opposite to cams 33 permits of air-tight engagement. Likewise, any suitable means may be provided at the lower part of the frame opposite to cams 36 to coact with the lowermost screen, such as plate 49 which may be arranged in front of the screen hinged to the top of the covered oil tank and normally urged into a loose open position by a spring thus serving to complete the seal at the bottom of the lowermost screen and still permitting an unobstructed lowering of it when so desired.

The screen sections S may be slidable in vertical guide and sealing grooves 50 tightly adjacent to box structures 14, said grooves 50 being formed for the several screen sections by vertical members 50a. When each of the screen sections has been elevated into its predetermined position for normal operation of the air cleaning device, and the cams aforesaid are brought to bear on the screens, cooperating means operated from one of the shafts 38 may be actuated to afford engagement at the side edges of the screens. A highly efficient structure can be made by providing vertical laterally movable locking bars 51 at the positions of elevation of the various screen sections, as will be understood from Fig. 3. Each of the bars 51 is mounted on arms 51a which are pivotally engaged with arms 52 that are secured to a vertical rocker shaft 53 journaled in brackets 54. A bevel gear 55 secured to shaft 53 meshes with a bevel gear 56 on the lowermost horizontal shaft 38 so as to cause a simultaneous operation of the cams and the bars 51 on rotation of handwheel 45. The opposite vertical sides of the screens are provided with similar sealing means and shaft 43 may be used for the operation thereof, taking the role of shafts 53, just described.

The vertical side frames or bars of each screen section are formed with central vertical grooves 57 to receive bars 51. Bars 51 may be slidable in a box structure comprising vertical plates 58 forming guides between which bars 51 are laterally movable. Reinforcing plates 59 are arranged for the guide plates 58, and the plates 50a between the screens help to form the guide grooves 50 for the screens. The whole structure will be obvious from the drawings, especially from Fig. 3, and it forms the mentioned box-like guide side frame which adjoins the box 14 and therewith forms a side frame for the filter screens. The guides are provided in said side frame only slightly higher than the travel of the respective screen requires and are there closed by top plates 62, as indicated in Fig. 2. The portions of boxes 50 which are not used for guiding the screen sections S in their movements are preferably formed as flat plates, as indicated at 50b, while those parts of the same which are in the paths of the movements of the screens may be provided with vertical central guide wedges 51b, similar in shape to bars 51 on which the frames 18 may loosely and easily slide. Simplification of this construction may be provided for by omitting either such central guide wedges 51b or the vertical separating guides 50a. Nuts 63 for the tie rods 18a may be disposed in recesses in the screen bars or frame 18, in any suitable manner, and so as to be clear of the locking bars 51. The rods 51a will be understood to be of varying lengths to correspond to the distance of the respective locking bars from shafts 53, and the length of arms 52 will vary accordingly. A sufficient clearance may be provided in the grooves within which the locking bars are movable to permit of easy sliding movement thereof, irrespective of the angular positions of arms 52, inasmuch as the angle of movement thereof is small. However, after being interlocked, a sufficient pressure will be created to insure a tight contact. Said locking bars, may, moreover be provided with cushioning felt strips 64 extending along the sides thereof and secured by screws 65, as shown in Fig. 5, and this combined with the wedge formation of the bars 51, will permit of tightness under any circumstances. However, I want to remark that the cams aforesaid may be sufficient to provide for air-tightness of the screens S all around their perimeters without any side bars 51, and such side sealing bars may possibly be entirely omitted with all their operating mechanism, thereby greatly simplifying the actual embodiment of the invention.

The cleansing of the screens is expedited by providing a movable container or basket 65 in the oil tank to receive the screens, said container having perforations 66 in the bottom thereof to permit of circulation of the oil when the container is moved. The front and back of said basket may also be eliminated and its end plates perforated for the said purpose. More specifically, basket 65 is operated by racks 67 at the ends thereof, meshing with pinions 68 on shafts 69 journaled in fixed brackets 70. Bevel gears 71 are secured

to shafts 69, and mesh with bevel gears 72 on a shaft 73 extending across the frame and through boxes 14 wherein the gears are housed. A crank handle 74 is rotated back and forth to alternately raise and lower the container 65, with the collapsed screen structure therein separated, bars 75 extending downward through perforations in the bottom of said container from the screen guide construction 50 described hereinbefore, to act as skeleton guides for the container and the screens therein when lowered. Skeleton guides 75 may rest on iron bars 75a. A rapid circulation of the oil through openings 66 and between the vertical plates of the screens will thus be obtained to effectively wash accumulations of dirt and foreign matter from the plates. The oil may then be drawn off, when desired, through a valve 76 in the bottom of the oil tank, and replaced by clean oil for further washing and for new oil coatings of the screen plates. A pawl and ratchet wheel indicated at 77, may lock shaft 73 in one direction against unintended movement under the weight of the screens.

The machine can be arranged to be operated wholly from outside of duct 11, as may best be seen from Fig. 3, and a suitable door may be placed in a wall of the duct adjacent to and in front of the machine to permit an operator to enter and inspect the machine from time to time.

It is thus seen that an air-cleansing device has been provided which is highly suitable to effectuate the objects of the invention, and which is practical and efficient. It may be built into an air duct and provide an airtight frame therein, leaving the air free travel only through the described oil coated screens to clean and purify the same. On the other hand, the elements of the improved filter can be loosened and dropped into the base oil tank with a few easy movements and operations and then thoroughly washed therein, as described.

I also again want to emphasize that while the herein described construction is a preferred embodiment of my invention, changes and variations may, however, be resorted to in the detail construction of the parts, or in the combinations and sub-combinations thereof, within the spirit of the invention and the scope of the claims hereinafter to follow.

I claim:

55 1. In a device of the character described, the combination of a fluid container, a receptacle in said container having openings in its walls a collapsible air screen, means to collapse said screen and to lower the same into said receptacle, and means to move about the receptacle in the fluid container for effective cleansing of the screen by fluid currents.

2. In a device of the character described, the combination of an air screen having a plurality of sections, means engaging one of

the sections to raise or lower the same, and means on said section to detachably engage another section to lift the same when the first mentioned section is raised, and to release the same when the first mentioned section is lowered.

3. In a device of the character described, the combination of a screen having a plurality of sections disposed in adjacent planes and overlapping one another, and means to press said sections into close engagement with one another.

4. In a device of the character described, the combination of a screen, means to movably support the screen, a frame to slidably receive the screen, and wedge means movable in the frame to engage the screen, said screen having a groove to receive said wedge.

5. In a device of the character described, the combination of an air screen composed of sections, means to collapse said screen by moving said sections into side by side relation to one another, a fluid container to receive said sections when collapsed, and means to circulate a fluid medium through said sections and said fluid container.

6. In a device of the character described, the combination of an air screen consisting of a plurality of sections disposed in adjacent planes, a frame structure with channels to guide said sections, and means to press the respective edges of any section into airtight engagement with the adjacent edge of the section above and with said frame.

7. In a device of the character described, a screen structure comprising superposed sections in adjacent relation, means to collapse said sections into side by side relation, and means to secure a substantially air-tight connection between the respective adjacent portions of the individual sections when the same are in operative position.

8. In an air screen, superposed individual sections in adjacent planes, guide means for said sections, and means to lower said sections in said guide means into side by side relation with one another, or to raise them into operative position.

9. In an air filter, the combination of a plurality of filter units mounted to be moved into side-by-side relation to each other, means for moving said units directly to extended position with one unit in edge-to-edge relation with another unit.

10. In an air filter, the combination of a plurality of filter units mounted to be moved into side-by-side relation to each other, means for moving said units directly to extended position with one unit in edge-to-edge relation with another unit, and means for exposing said units while in side-by-side relation to a bath of fluid.

11. In an air filter, the combination of a frame, guide channels therein, a plurality of filter units mounted to be moved in said

channels into side-by-side relation to each other, and means for moving said units to extended position with one unit in edge-to-edge relation with another unit.

5 12. In an air filter, the combination of a plurality of filter units mounted to be moved into side-by-side relation to each other, a receptacle positioned and adapted to receive said units when the latter are in said side-by-side relation, and means for moving said units to extended position with one unit in edge-to-edge relation with another unit.

10 13. Air filter apparatus comprising a series of filter units mounted in filtering position with the end of one unit adjacent to the end of another unit, means for collapsing said units to side by side relation, and means for cleaning said collapsed units.

15 Signed at New York, in the county and State of New York, this 19th day of March, 1927.

CHARLES H. GAGEN.
